(57) **CLAIM**

The ornamental design for a pop up cargo tote, substantially as shown.

DESCRIPTION

FIG. 1 is a perspective view of a pop up cargo tote according to an embodiment;

FIG. 2 is a front view of the pop up cargo tote according to the embodiment;

FIG. 3 is a rear view of the pop up cargo tote according to the embodiment;

FIG. 4 is a right side view of the pop up cargo tote according to the embodiment;

FIG. 5 is a left side view of the pop up cargo tote according to the embodiment;

FIG. 6 is a top view of the pop up cargo tote according to the embodiment;

FIG. 7 is a bottom view of the pop up cargo tote according to the embodiment;

FIG. 8 is a perspective view of the partially collapsed pop up cargo tote according to the embodiment;

FIG. 9 is a perspective view of a fully collapsed pop up cargo tote according to the embodiment;

FIG. 10 is a side view of a fully collapsed pop up cargo tote according to the embodiment; and,

FIG. 11 is a top view of a fully collapsed pop up cargo tote according to the embodiment.

The broken line elements in all views are for illustrative and environmental purposes only and form no part of the claimed design.

1 Claim, 6 Drawing Sheets
